(57) **CLAIM**

The ornamental design for a “ball thrower,” as shown and described.

DESCRIPTION

FIG. 1 is a perspective view of the ball thrower;
FIG. 2 is a back view of the ball thrower;
FIG. 3 is a bottom view of the ball thrower;
FIG. 4 is a front view of the ball thrower;
FIG. 5 is a left side view of the ball thrower;
FIG. 6 is a top view of the ball thrower;
FIG. 7 is a right side perspective of the ball thrower; and,
FIG. 8 is a left side perspective view of the ball thrower.
The broken lines shown in the drawings form no part of the
claimed design.
